(57) **CLAIM**

The ornamental design for a writing utensil, as shown and described.

DESCRIPTION

FIG. 1 is a front view of the writing utensil;

FIG. 2 is a rear view of FIG. 1;

FIG. 3 is a plan view of FIG. 1;

FIG. 4 is a bottom view of FIG. 1,

FIG. 5 is a right side view of FIG. 1, the left side view being a mirror image;

FIG. 6 is a cross sectional view of FIG. 5; and,

FIG. 7 is a cross-sectional view of FIG. 5 with the cap member removed for ease of illustration.

The broken line showing is for illustrative purposes only and forms no part of the claimed design.
